SAND DELIVERY PIPE NOZZLE

Guilford S. Turner, Jr., Chicago, Ill., assignor to
 Morris B. Brewster Co. Inc., Chicago, Ill., a corporation of Illinois

Application November 18, 1949, Serial No. 128,157

1 Claim. (Cl. 291—46)

1

The invention relates to nozzles for discharging sand from a delivery pipe onto a railway rail.

In practice it has been found that nozzles for this purpose generally become clogged with ice or other material. One object of the invention is to provide a nozzle which minimizes clogging and which, if it becomes clogged, can be cleared by the blast of sand from the delivery pipe.

Other objects of the invention will appear from the detailed description.

The invention consists in the several novel features hereinafter set forth and more particularly defined by a claim at the conclusion hereof.

In the drawings:

Fig. 1 is a diagrammatic view of a locomotive wheel and a sand-delivery pipe equipped with a nozzle embodying the invention; and

Fig. 2 is a longitudinal section of the nozzle.

The invention is exemplified in a one-piece nozzle which is formed of elastic material, such as suitable rubber, which is detachably connected to a pipe 10 from a trap through which sand is delivered into pipe 10 by air under pressure. The inlet end of the nozzle is usually connected by a hose coupling 12 to the lower end of pipe 10. The lower end of the pipe 10 is usually supported from the truck-frame and the nozzle is positioned to direct the sand between the railway rail 14 and the locomotive drive wheel 16, as well understood in the art.

The nozzle is formed in one piece with a tubular body 18 of elastic material. The sand-delivery pipe 10 extends into the inlet end of the bore 19 and the nozzle is secured on said pipe by a suitable clamp 12 which fits against an annular shoulder 21 on body 18. The bore 19 extends outwardly from the end of pipe 10 and terminates, as at 22, at the outer end of an annular wall 23 of the body 18. The body is provided with a tubular wall 26 which forms an integral extension of elastic material and provides a discharge orifice 27 which is spaced outwardly from the end 22 of bore 19. The annular wall 26 has a tapered inner peripheral portion 28, a tapered outer peripheral portion 29, and a straight inner peripheral portion 30 which extends around and is spaced from the wall 23 in body 18 to extend the chamber in the extension around wall 23. This extension with the internal periphery described forms an expansion chamber between the outer end 22 of bore 19 and the discharge orifice 27 of tubular wall 26 and around the outer end of the wall 23 of the body at the discharge end of bore 19.

In operation, air under pressure from the sand trap forces the sand through the bore 19 and the expansion chamber and is finally discharged at the orifice 27 at the outer end of the annular wall 26. The pressure of air in this expansion

2

chamber exerts an outward pressure on the tapered elastic annular wall 26 and flexes the wall to aid in loosening any adhering material. The tapered outer periphery of wall 26 tends to deflect the water away from the outer end of the nozzle. Water which enters the lower portion of the expansion chamber through orifice 27 will be retained in the lower portion of the chamber and under the discharge end 22 of bore 19. This lessens the likelihood of obstructing the outer end of the bore. If under extreme climatic conditions, ice forms in or across the orifice 27, the next time sand and compressed air are delivered into the nozzle through bore 19 the pressure will flex and expand the elastic tapered wall 26 and loosen the obstructing material so it will be discharged outwardly from the orifice 27 to clear the nozzle.

The invention is not to be understood as restricted to the details set forth since these may be modified within the scope of the appended claim without departing from the spirit and scope of the invention.

Having thus described my invention, what I claim as new and desire to secure by Letters Patent is:

A sand pipe nozzle comprising a one-piece tubular body of elastic material having a bore, the inner end of which is adapted for connection to a pipe for delivering sand under air pressure into the bore, the body having an integral inner cylindrical wall at the outer end of the bore, and an outer integral cylindrical wall radially spaced from and adjacent the outer end of the inner cylindrical wall to provide an annular channel between the inner and outer cylindrical walls, the body being provided with an outwardly tapered integral extension from the outer cylindrical wall terminating in an outlet outwardly beyond the outer end of the inner cylindrical wall, the extension forming a tapered portion which is expandable by pressure developed in the extension by fluid from the bore.

GUILFORD S. TURNER, JR.
